United States Patent Office.

JOSEPH I. BELL, OF BELL'S BRIDGE, CALIFORNIA.

Design No. 4,458, dated November 8, 1870.

DESIGN FOR A BUCKLE.

The Schedule referred to in these Letters Patent and making part of the same.

To all to whom it may concern:

Be it known that I, JOSEPH I. BELL, of Bell's Bridge, county of Shasta, State of California, have invented an Improved Buckle; and I do hereby declare the following description and accompanying drawing are sufficient to enable any person skilled in the art or science to which it most nearly appertains to make and use my said invention or improvement without further invention or experiment.

The nature of my invention consists in the design for a buckle represented in the above-mentioned drawing, the same consisting of a circle or ring, A, surrounding an oblong rectangular buckle-frame, b b,

which frame is provided with a middle-bar, i, and tongue, c, all the above-mentioned parts being constructed and arranged as represented in the drawing.

What I claim as my invention is—

The design or configuration for a buckle, as described and shown.

In witness that the above-described invention is claimed by me, I have hereunto set my hand and seal.

JOSEPH I. BELL. [L. S.]
